ELECTRONIC STORAGE TUBE CONTROL
SYSTEM

Rudolf C. Hergenrother, West Newton, Mass., assignor to Raytheon Manufacturing Company, Newton, Mass., a corporation of Delaware

Application December 15, 1948, Serial No. 65,472

5 Claims. (Cl. 315—9)

1

This invention relates to electron discharge device, and more particularly to a control device for controlling the position of an electron beam in an information storage tube, for example, the type shown in my copending application, Ser. No. 64,222, filed December 8, 1948, now Patent Number 2,548,789, issued April 10, 1951.

In storage tube systems of the type disclosed in said copending application, it is extremely difficult to accurately locate particular points on the target area. Therefore, when information has been stored at a particular point on the target by directing the electron beam thereto and charging said spot with said beam, it is difficult to again locate that particular spot on the target so that the information thereon may be read and used. The difficulty lies in the fact that any changes in the power supply or the deflection generator voltage causes a change in the position of the beam. Furthermore, the smaller the area to be located, the closer the tolerance must be in the variations in voltage and other circuit parameters.

In addition, when a series of memory units are used, there is no way of insuring that the information on each tube would be read in correct synchronism to that of the other tubes since as aforesaid the voltage and other circuit parameters of the tubes might vary between the time when the information was applied to the tube and the time the information was read off from the tube. Further, when tubes were interchanged as, for example, when replacement was necessary, it was required that the system be recalibrated to conform to any slight variations in the structure of the replacement tubes.

Accordingly, it is an object of the present invention to provide a control device whereby memory tubes may have their electron beams repeatedly and accurately positioned on any particular spot on the target.

Another object of the invention is to provide a control device which will eliminate the necessity of having a restricted storage space on the storage target of the memory tube for each particular piece of information, but rather the storage surface may be continuous so that the pattern of storage elements is not restricted or preassigned.

Still another object of this invention is to provide a control device whereby several memory tubes may be synchronized so that their respective beams may be accurately and simultaneously positioned in any particular spot on their respective target surfaces.

The foregoing and other objects of the inven-

2

tion will best be understood by reference to the following description of an exemplification thereof, and to the accompanying drawings, wherein:

Fig. 1 represents one modification of the invention wherein information positioned at any particular point on the storage surface may be located at will; and

Fig. 2 represents a further modification of my invention wherein the storage target area may be scanned repeatedly over precisely the same path in the scanning raster.

Referring now to Fig. 1, there is disclosed a vertical sweep monitor tube 10 and a horizontal sweep monitor tube 11 controlling the sweep circuits which feed the deflection plates of an information storage unit schematically shown at 13 having an information storage surface 13a.

It is to be clearly understood that the circuit described is by way of illustration only and any desired control circuit may be used in conjunction with the monitor tubes and memory unit. Furthermore, while the preferred modification of my invention employs two monitor tubes, one for the vertical sweep, and one for the horizontal sweep, this is not absolutely necessary since both units could be consolidated into a single monitor tube having both horizontal and vertical deflection plates and horizontal and vertical monitoring slots in the target.

The vertical monitor tube 10 comprises an electron gun 14, consisting of a cathode 15, a grid 16, a focusing anode 17 and accelerating anode 18. The electrodes of this gun are energized with suitable voltages, for example, from taps on a resistor 50 which is connected at one end to the accelerating anode 18 and to ground, and at the other end to the grid 16 and a source of negative potential of roughly 1500 volts. The correct density and focus of the beam projected from the gun 14 are produced by connecting the cathode 15 and the focusing anode 17 to suitable taps on the resistor 50.

The beam is deflected vertically in response to voltage applied between a pair of deflecting plates 19, one of which is connected to ground and the other of which is connected to a suitable deflection voltage generator 20. The beam is directed toward an electrode 21 consisting of a flat plate with a series of horizontal slots cut therein and which is connected to ground potential. Behind this electrode 21 is a second conducting electrode 22 such that when the beam is directed toward a slot in the flat plate 21 it will pass therethrough and strike the adjacent electrode 22. The electrode 22 is connected to

ground through a load resistor 23. A shield 47 surrounds the space between the deflection plate 19 and the electrode 21 to prevent external electric field from affecting the electron beam.

Thus it may be seen that if the beam is moved vertically it will pass over the slots in the electrode 21, and each time it crosses one of the slots a stream of electrons will strike the electrode 22 causing an output voltage pulse to appear across the resistor 23.

The output voltage pulses developed across the resistor 23 are fed into a counting circuit 31 which may be any of the counting circuits well known in the art, for example, a ring counter, wherein a series of electron tubes are successively turned on or off by a series of pulses until, when a certain number of pulses have been received, a particular tube conducts, producing a large output pulse. In this case the number of pulses is preset, for example, by a train of pulses introduced to the counting circuit for that purpose. The output from the counting circuit 31 is used to trigger electronic switch 24 which, for example, may be of the triggered multivibrator type wherein two tubes are used in a circuit such that, if the grid of one is triggered by a positive pulse, it will cause that tube to conduct and the other tube to be cut off. Then when a positive pulse is introduced onto the grid of the tube which is cut off, it will cause that tube to conduct and the first-mentioned tube to be cut off. The output from the switch, which may, for example, be taken from one of the plates through a suitable blocking condenser, is used to apply a rectangular pulse to the grid 25 of a constant current generator which acts as the deflection voltage generator 20 to feed the deflection plates 19 by charging up the capacitance between the plates. The constant current generator circuit 20 consists of a pentode whose plate is attached directly to the ungrounded plate of the monitor tube 10. The suppressor grid 26 of the pentode is connected directly to the cathode 27 which is connected to ground through a battery 45 which maintains the cathode at a potential of a few hundred volts negative with respect to ground. The screen 28 is grounded. The grid 25 is normally maintained below cutoff by being connected to the cathode 27 through a grid resistor 29 and a bias battery 30.

Upon the application of a positive pulse from the electronic switch 24 to the grid 25 of the deflection voltage generator 20 the tube is caused to conduct, charging the capacitance existing between the two deflection plates 19. This causes the beam to sweep across the slots in the electrode 21 producing output pulses on the electrode 22. When a certain number of pulses are received by the counter circuit 31, it triggers the grid which is below cutoff potential of the electronic switch 24, causing a negative pulse output to cut off the generator 20. The deflection voltage applied to the plates 19 remains there and the electron beam remains positioned on the slot which produced the last pulse which triggered the counting circuit.

Thus it may be seen that, by presetting the counting circuit 31 by a train of pulses such that it will count up to a predetermined number of pulses, the electron beam can be made to sweep across that number of slots on the electrode 21 and be automatically halted in position on the slot corresponding to the last pulse. In order that the deflection beam may be reset to zero to begin counting to a different position, a retrace circuit 32 is used.

This retrace circuit comprises a gas tube having a plate 33 which is attached to ground through a battery 34 such that the plate is maintained at a suitable constant positive potential above ground. The cathode 35 is connected directly to the ungrounded deflection plate 19. A screen grid 36 is maintained at a suitable operating voltage above the cathode 35, for example, 100 volts, by means of a battery 37. The grid 38, upon being triggered by a positive pulse from the reset circuit, will cause the tube to fire, thus discharging the capacitance between the plates 19 until a value is reached where the voltage drop across the gas tube is so low that it ceases to fire. This deflects the beam vertically downward. The voltage of battery 34 is chosen such that the beam comes to rest at a point below the lowest slot in the electrode 21. This represents the beam's zero or starting point. The gas tube will then not fire again until its grid is again triggered by a zero reset pulse.

The plates 19 are directly attached to corresponding vertical deflection plates 46 of the memory unit 13, whose action is more completely described in the aforementioned copending application. The horizontal deflection plates 46b of the memory unit 13 are connected directly to corresponding deflection plates 19b of a horizontal monitor tube 11 which is in all respects similar in operation to the vertical monitor system. The various components of the horizontal monitor tube system are numbered similarly to those of the vertical monitor tube system with the addition of the suffix b.

To locate any particular spot on the storage plate (not shown) of the storage unit 13, its characteristic location numbers are set up in the counter circuits 31 of the vertical monitor tube system and 31b of the horizontal monitor tube system. For example, if it is wished to locate a point on the target which corresponds to four slots up on the vertical monitor tube screen and seven slots over from the zero position in the horizontal monitor tube screen, the counting circuit 31 would be set to count four pulses before producing an output and the counting circuit 31b would be set to count seven pulses. The respective electronic switches 24 and 24b are then triggered simultaneously to produce positive output pulses, thus starting scanning circuits. The vertical monitor tube will cause the vertical scanning circuit to stop after hitting the fourth slot, and the horizontal counting circuit will stop the horizontal scanning circuit after hitting the seventh slot. Since the plates of the memory unit are connected in parallel with the plates of the monitor tubes, the beam of the memory unit will be accurately positioned on the storage target at a position corresponding to four slots vertical and seven slots horizontal deflection.

Thus it may be seen that, when it is desired to store information on the storage target on a particular spot, for example, the above-mentioned position four vertical, seven horizontal, the beam of the storage unit is positioned thereon by the monitor units and the information storage operation is then carried out. If sometime later, for example, days or weeks, it is desired to read the information stored on this particular spot, the coordinates four vertical and seven horizontal are again set up in the counting circuits and the beam is then automatically and with extreme accuracy repositioned on the spot where the information was stored.

While I have shown here a monitor tube target

electrode system comprising a slotted electrode 21 and a signal electrode 22, it will be obvious to those skilled in the art that other electrode arrangements may be used for producing output pulses when scanned by a beam. For example, a target electrode might consist of two materials having different secondary emission properties, for example, a background material of aluminum with lines of carbon on its face in place of slots. Due to the different secondary emission characteristics, different target currents will occur when the beam strikes each of the two materials.

Referring now to Fig. 2, there is shown an embodiment of my invention wherein the scanning generators repeatedly scan precisely the same path. Herein there exists a vertical monitor tube 10 which is essentially similar to that of Fig. 1. However, the electrode 22 is divided into two electrodes 22 and 22a, the electrode 22 being struck by electrons passing through any of the slots in the electrode 21 except the uppermost. Electrons passing through the uppermost slot strike the electrode 22a. The scan and retrace circuits 20 and 32 are precisely the same as that of Fig. 1 and the deflection plates are connected to corresponding deflection plates of a memory unit 13. The output of the electrode 22 is developed across one of the resistors 23 and feeds a mixer circuit 39 which consists of any means for blocking two signals, fed to a common output, from cross-feeding into their respective sources, for example, a pair of electron tubes having their plates in parallel to feed the common load and their grids fed by the respective sources. The output of the mixer feeds the stop pulse to the electronic switch 24 for stopping the scan generator 20.

Now an input trigger pulse for starting the sequence of events is fed through a mixer circuit 40 to trigger the electronic switch 24 to cause a positive output therefrom. This initiates the scanning by the generator 20. The beam of monitor tube 10 which, due to the zero reset action described in Fig. 1, is below the lowest slot in the electrode 21 moves upward, crossing the first slot. The output pulse appearing on electrode 22 feeds through the mixer 39 to trigger the electronic switch 24, stopping the scan generator. The output from electrode 22 also triggers the electronic switch 24b which initiates the scanning circuit 20b of the horizontal monitor system 11. The horizontal monitor tube is similar to that of Fig. 1 except that the electrode 21 has only two vertical slots which are spaced apart by a distance equal to the desired length of the horizontal sweep. Behind each of these slots is an electrode 22b and 22c.

The horizontal scan generator 20b is similar to that of Fig. 1. However, the retrace circuit uses a vacuum tube rather than a gas tube. This tube 48 has its plate 49 tied to ground through a plate supply battery 50, its suppressor grid 51 tied to the cathode 52 which is connected directly to the ungrounded deflection plate 19b of the monitor tube 11. The screen grid 53 of tube 48 is maintained at a suitable positive potential with respect to the cathode 52 by a battery 54 connected therebetween. The grid 55 is maintained below cutoff by being connected to the cathode 52 through a grid resistor 56 and a bias battery 57.

An electronic switch 41 having its inputs connected to the electrodes 22b and 22c, respectively, feeds a positive pulse to the grid 55 of the retrace tube 48 when the beam of monitor tube 11 produces a pulse on electrode 22c, thus initiating the retrace.

Prior to energization of the scan generator 20b the beam may be, for example, positioned at one side of the target beyond both slots. As the scanned generator causes the beam to sweep, the beam crosses the slot in front of the electrode 22b, which is the retrace stop electrode, and produces a pulse thereon, but with no effect since the retrace circuit is already stopped. The scanning proceeds until the beam has crossed the electrode 21 reaching the other slot, whereupon it produces an output on the electrode 22c. The output from this electrode is fed to the negative pulse, grid circuit of the electronic switch 24b, thus stopping the scanning circuit. The pulse is also fed to the start circuit of an electronic switch 41 which, as already described, causes energization of the retrace tube 48 causing the beam to be deflected back towards its original position.

Upon striking the slot in front of the electrode 22b, an output pulse appears on said electrode which feeds a pulse to the negative output grid of the electronic switch 41 stopping the retrace. The beam is then positioned on the slot in front of electrode 22b.

At the same time that the beam of the horizontal scan is retracing, the pulse from electrode 22c is fed through the mixer 40 to the start grid of the electronic switch 24 initiating scanning by the vertical scan generator. This produces a diagonal retrace on the target of the memory unit 13.

It is essential, in this particular circuit, that the retrace of the horizontal scan generator be complete before the vertical scan beam reaches the next slot in its target electrode 21, so that the vertical scan generator 20b will be in condition to be again triggered by the output from the electrode 22.

This cycle automatically continues until the vertical sweep generator moves the beam to the uppermost slot of the electrode 21, causing a pulse to appear on the electrode 22a. Since no trigger pulse is fed the electronic switch 24b, the horizontal scan generator 20b remains in its retraced position. The output from 22a is fed into an electronic switch 42 causing a negative pulse to be fed to the grids of both the monitor tubes with the result that their electron beams are cut off.

The electronic switch 42 also feeds a positive pulse, through a differentiating circuit, which creates a sharp pip, to the gas tube in the retrace circuit 32 of the vertical monitor tube deflection system 10, thus causing the vertical deflection plates 19 to move the beam back to its original starting position. The beam will then remain there until an input trigger pulse again starts the vertical scan generator. This input pulse is simultaneously fed to the opposite grid of the electronic switch 42 from that connected to the electrode 22a. This removes the cutoff pulse applied to the grids of the monitor tubes. The resultant negative pulse applied through the differentiating circuit 43 has no effect on the retrace generator circuit 32 since the gas tube is already cut off.

Thus it may be seen that every time an input trigger pulse is fed into the circuit, the system will cause the storage target of the memory unit to be scanned along a predetermined path. Thus information may be stored on the device 13 by initiating the scanning action and continuously storing information on the target. Later when it is desired to reread the information the scan

sequence is then initiated and the information will again appear in its correct sequence.

It may be noted that the information may be recorded by operating the scanning system at a high speed and then later reading the information at a much slower rate by slowing down the scanning speed of the deflection generators to a slower speed.

It is to be clearly understood that the particular scanning raster used herein is by way of example only and any desired scanning raster may be used. For example, the well-known scan may be used where the horizontal sweep would move the beam across the target, the vertical scan would then raise the beam by one line, and the horizontal scan would move back across the target. The vertical scan would then raise the beam another line and the horizontal beam would scan across the target again. This process would be repeated until the top of the target had been reached, whereupon the vertical retrace occurs as heretofore described.

It is to be clearly understood that the aforementioned illustrations of my invention are by way of example only and other modifications will be apparent to those skilled in the art. Therefore, it is desired that the appended claims be given a broad interpretation commensurate with the scope of the invention within the art.

What is claimed is:

1. A memory device comprising information storage means comprising a charge retaining surface, means for storing information on said storage means, and means for directing said storing means to a particular storage position comprising an electron discharge device having a source of electrons and an electrode, and means for directing electrons from said source to a position on said electrode corresponding to said particular storage position, said electron directing means being functionally related to said storing means directing means.

2. A memory device comprising information storage means comprising a charge retaining surface, means for storing information on said storage means, and means for directing said storing means to a particular storage position comprising an electron discharge device having a source of electrons and an electrode, means for beaming said electrons toward said electrode, and means for controlling the position of said beamed electrons and said means for directing said storing means in response to any predetermined one of a group of numbers of output pulses

from said electrode, said electron directing means being functionally related to said storing means directing means.

3. A memory device comprising information storage means comprising a charge retaining surface, means for storing information on said storage means, and means for directing said storing means to a particular storage position comprising an electron discharge device having a source of electrons and an electrode, means for forming said electrons into a sharply defined beam, means for directing said electron beam to various positions on said electrode, and means for controlling said electron beam and said means for directing said storing means in response to the output from said electrode.

4. A memory device comprising an electron discharge device having a source of electrons and a storage plate, means to direct said electrons to particular positions on said plate to store thereon charges representative of information comprising a second electron discharge device having a source of electrons and an electrode, means for directing said electrons toward said electrode, and means for simultaneously controlling the electron directing means in both said electron discharge devices.

5. A memory device comprising an electron discharge device having a source of electrons and a storage plate having a homogeneous surface, means to direct said electrons to particular positions on said plate to store charges representative of information comprising a second electron discharge device having a source of electrons and an electrode, means for directing said electrons toward said electrode, and means for simultaneously controlling the electron directing means in both said electron discharge devices in response to output signals from said second electron discharge device.
